Fig. 2.

Inventor:

Ernest Leonard Marley.

Attorney: O. J. Wadsworth

UNITED STATES PATENT OFFICE.

ERNEST LEONARD MARLEY, OF BRIGHTON, ENGLAND.

SIGNALING DEVICE.

Application filed January 6, 1921. Serial No. 435,392.

To all whom it may concern:

Be it known that I, ERNEST LEONARD MARLEY, of Brighton, England, a subject of the King of England, have invented certain new and useful Improvements in Signaling Devices, of which the following is a specification.

This invention relates to a new or improved visual, and if desired, audible indicator for signaling purposes, more particularly for use in connection with self-propelled vehicles, although the device is capable of use in any other capacity where signaling is required as on ships, railways, etc.

An object of the invention is to provide a simple cheaply constructed and efficient indicator of the semaphore type whereby both visual and if desired audible signals may be given. An indicator according to this invention comprises an arm having one or more transparent surfaces and a lamp therein with means for rotating said arm through a pre-determined number of degrees, whereby upon the movement of the arm the light rays will pass through a visual indicating medium, or also through the audible medium, if present, or through both simultaneously.

Another object of the invention is to provide a special construction of semaphore signaling arm in the form of an arrow adapted to revolve about its centre.

In order that the invention may be clearly understood, practical applications of the invention will now be described by aid of the accompanying drawings in which:—

Fig. 1 is a sectional elevation of a complete signaling device embodying the invention. Fig. 2 is a front view thereof.

Referring to the drawings, the indicator therein shown is formed of a frame 29 preferably shaped like an arrow and having translucent or transparent fillings 30 and tapering chambers 31 behind said fillings acting as reflectors whereby the rays from a centrally placed electric lamp 32 may, at certain times, be reflected to illuminate said filling.

At the centre of the indicator is a sleeve 34 surrounding a fixed sleeve 35 carrying the lamp 32 and co-operating mechanism. These sleeves are provided with perforations 36 and 37 respectively whereby in certain positions of the indicator angularly

about the fixed sleeve the rays of the lamp may pass, whereas in other positions such rays are obscured. Lenses or coloured glasses may be arranged in some of said perforations.

The arrangement is preferably such that when the indicator is upright and pointing downwards meaning for example "straight on", its transparent fillings 30 are not illuminated; when turned from such position through about 45 degrees, the transparent filling will become illuminated, and in such position also a switch may make contact to an audible warning signal not shown. On passing this warning position the audible signal may cease, but the indicator will remain illuminated. The operator may, however, arrest the indicator at the completion of 90, 180 or 270 degrees of revolution, thus indicating respectively an intended turn to the right, stop and turn to the left. At the "stop" position the indicator will preferably be illuminated through a red lens or glass.

This device may be combined with means for showing a red light as usually shown by back lamps of motor cars. For this purpose the fixed sleeve aforesaid is shown as capped at the end by a red lens or glass 33.

In order that the device may also serve for illuminating a permanent indicator such as a number plate, there may be fitted an annular window 38 preferably rearward of and forming part of the indicator sleeve through which the light rays may pass in all positions of the indicator but to confine such rays to the direction required the inner fixed sleeve may carry a suitable mask 39 provided with an opening or openings only where the light is to issue.

The rotatable sleeve 34 is revolvably mounted on an extension 35^a of the fixed sleeve and under the action of a spring 40 which tends to return it to normal position, after release of the operating means. The rear end of the device is also shown as enclosed in a casing 41 closed by a cap 42 with the exception of an aperture 43 through which pass the lamp conductors 44 which are enclosed within the device by a tube 45. The rotatable sleeve is held in its positions of adjustment against accidental displacement by a spring catch 46 adapted to engage apertures corresponding to said positions.

What I claim as my invention and desire to secure by Letters Patent of the United States is:—

1. In an indicator for the purpose specified, a supporting sleeve having a chamber in its outer end and openings at predetermined spaced points in its sides; a light in said chamber; a second sleeve rotatably mounted on the first sleeve, and surrounding the said chamber, said second sleeve having openings adapted to register with the openings in the first sleeve at predetermined rotatably displaced positions of the second sleeve upon the first sleeve; an arm connected to said rotatable sleeve and projecting on diametrically opposite sides thereof, said arm having a chamber at each side of the sleeve each chamber having a transparent closure in its front side, said chambers being illuminated only when the openings in the rotatable sleeve register with the proper openings in the first sleeve; and means for holding the rotatable sleeve and arm normally in such position that the

chambers are not illuminated; and means for rotatably displacing the arm and movable sleeve on the fixed sleeve to certain predetermined positions wherein the openings in the sleeves register so that the chambers in the arm are illuminated.

2. In an indicator as set forth in claim 1, the rotatable sleeve having a window opening exterior to the arm, and the inner sleeve having an opening whereby light may pass to and through said window.

3. In an indicator as set forth in claim 1, a casing supporting the first sleeve, and a spring in said casing for returning the rotatable sleeve and arm to normal position on the first sleeve.

In witness whereof I have signed this specification in the presence of two witnesses.

ERNEST LEONARD MARLEY.
